UNITED STATES PATENT OFFICE.

NICHOLAS L. GULLIFORD, OF PEABODY, MASSACHUSETTS, ASSIGNOR TO GREGORY & READ COMPANY, OF BOSTON, MASSACHUSETTS, A CORPORATION OF MASSACHUSETTS.

ART OF WOOD-HEEL MAKING.

Application filed August 21, 1923. Serial No. 658,647.

To all whom it may concern:

Be it known that I, NICHOLAS L. GULLIFORD, a citizen of the United States, and a resident of Peabody, in the county of Essex and State of Massachusetts, have invented certain new and useful Improvements in the Art of Wood-Heel Making, of which the following is a specification.

This invention relates to the art of wood heel making and is particularly concerned with the shaping operation by which the breast face or exterior under outer side of the forwardly projecting shank lip of the heel is convexly curved to conform to the transverse curvature of the shank of the shoe to which the wood heel is applied, and is in the nature of an improvement in the practice, and upon the apparatus described in my Letters Patent of the United States #1,433,002 dated October 24, 1922.

Wood heels are commonly made for use on women's shoes and are usually of the style or type known as Louis or French heels. For such use the heels must, when finished, present smooth clean-cut surfaces and corners, and in the operation of cutting the superfluous stock from the heel to give the shank portion of the breast the desired transversely arched or convex shape, it is of much importance to avoid a substantial percentage of loss or waste through breakage or the production of an undesirable number of imperfect heels having ragged or splintered corners on the side where the shank shaping cutter leaves the work.

To this end my invention comprises a method and a means for providing such backing or support against the thrust of the cutter for the side of the heel adjacent the corner formed by the shank shaping cutter at the junction of said side and breast as it leaves the work, that chipping, tearing or splitting of the wood is prevented and a sharply defined and clean-cut corner is produced.

In explanation of my improved process and apparatus I have shown a machine or apparatus of the type described in my aforesaid patent, which machine operates upon a partially formed wood heel; that is, a wood heel that is completely shaped with the exception of the operation of shank shaping, but the present invention is not limited to apparatus of that particular type.

In the accompanying drawings:

Figure 1 is a side elevation of a heel shaping machine having a work holder constructed in accordance with my invention.

Figure 2 is a plan view of a portion of the machine shown in Fig. 1.

Figure 3 is a detail, on larger scale, of the work holder of the machine shown in Figs. 1 and 2, a wood heel being shown in position therein.

Figure 4 is a perspective view of the work holder shown in Fig. 3.

Figure 5 is a plan view of one form of mold that may be used in carrying out my invention.

Figure 6 is a sectional view of the mold shown in Fig. 5.

Figure 7 is a section on line 7—7 of Figs. 5 and 6.

Figure 8 is a perspective view of a wood heel before being operated upon by the machine herein shown.

Figure 9 is a perspective view of one of the jaws hereinafter described, showing the same partially completed.

The machine herein shown comprises a rotatable internal cutter head 1 mounted upon a shaft 2 journaled in stationary bearings on the frame, said cutter head being disposed opposite a work holder 3 that is mounted upon a carriage 4 movable toward and from the cutter head. Cutter head 1 carries cutting blades 5 each having a curved cutting edge corresponding in shape with the shape that is to be given to the shank and upper portion of the breast of the heel. The heel that is to be operated upon is placed upon the bed 9 of the work holder between two holding jaws 6 and 7 by which it is clamped and held immovable upon the bed 9 while the carriage 4 and the work holder are moved toward and from the cutter head. When the carriage is moved toward the cutter head to the limit of its movement in that direction as determined by the stops 8, the shank portion *h* of the heel *H* is carried into position against the outer ends of the blades 5 and also between said blades and the axis of the cutter head as fully described in my patent referred to above, so that said blades sweep across said shank portion and give to the same a transversely convex shape as shown in Figs. 3 and 4, said shank portion being originally of the shape shown in

Fig. 8 and being reduced by this operation, at the shank end of the breast, to a very thin edge owing to the fact that the top of the heel is concaved to fit the convex portion 5 of the heel of the shoe to which it is applied. It will therefore be clear that the cutters reduce the shank end of the breast of the wood heel to very frail and weak proportions so that, in a machine of this kind, unless the 10 material of the heel at the side of the breast immediately adjacent the latter is supported against the thrust of the cutting blades, particularly at the rear side of the heel with respect to the direction of movement of the 15 blades, where the latter leave the work, the heel block will often be broken, splintered, split or otherwise deformed and spoiled. Furthermore, blanks for wood heels are produced by a method which disposes the grain 20 of the wood fore and aft of the heel so that the breast shaping cutters travel across the grain and, therefore, if the material of the side of the heel is not backed up and supported as pointed out the heel block is liable 25 to be splintered, split or made ragged at any place within the range of the cutting edges of the blades. Heretofore, when operating upon heels, or heel blanks without such side support the percentage of loss 30 through breakage, ragged corners, splintering and the like, has been very large. My present invention completely eliminates this loss and it contemplates both improved apparatus for shaping the breast portions of 35 wood heels, or heel blanks, and involves a novel method of making the same, particularly the work holding means thereof.

The jaw 6 is provided with a shank 10 formed with a slot 11 to receive a bolt 12 40 by means of which latter the shank and jaw are clamped rigidly to the bed 9. The opposite jaw 7 is fast to the end of the slide bar 13 which is manually operated and controlled as described in my prior patent. The 45 heel to be operated upon by the machine has its shank portion shaped as in Fig. 8 and is placed between the two jaws 6 and 7 and jaw 7 is pressed and held firmly against the heel while it is being operated upon by the cutter head.

The inner work engaging face of each jaw has a shape that is a counterpart of the shape of the side of the heel engaged by it, so that when a heel is clamped between the 55 two jaws the latter fit against the sides of the heel throughout the area of each work engaging face, and thus the heel is held against movement in any direction.

As will be clear from Fig. 3, which is an 60 elevation of the heel holder viewed away from the cutter head, the fixed jaw 6 is the rear or abutment jaw of the pair and supports the work against the thrust of the cutting blades, while the chief function of the 65 opposite jaw 7 is to hold the work against

the rear fixed jaw 6 and to co-operate with the latter in holding the work down upon the bed 9. The cutting blades, rotating in the direction of the arrow in Fig. 3, pass above the shank portion of the breast and 70 shape the latter between the points h' and h^2 , Fig. 8. There is, of course, little or no tendency on the part of the cutters to split or splinter the work as they come into engagement with the same adjacent the jaw 75 7, but unless the jaw 6 properly backs up and supports the heel at the opposite side thereof, the cutters will injure, and frequently destroy the heel. For this reason the work engaging face of the jaw 6 is made 80 of a shape and size to engage the side of the heel immediately adjacent the curved corner thereof at the junction of the rearmost side of the heel with the breast thereof from the point h' to the point h^2 . That is to say, 85 the work engaging face of the jaw 6 is made with a heel engaging and supporting side edge portion 6^a conforming in shape to both the side and breast of the heel, said edge portion being co-extensive with the cut made 90 by the blade, or blades, and coinciding with the corner of the heel as finally shaped by the cutter head. Preferably the jaw 7 is a 95 counterpart of the jaw 6 but this is not essential.

To produce the jaws 6 and 7 I may provide and use a mold such as shown in Figs. 5, 6 and 7. This mold comprises a base section 14 and two top sections 15 and 16 held in proper positions relatively by means of 100 dowels 17. The mold sections are formed so that when assembled they provide a cavity 18 within which is placed the ends of the slide bar 13 and shank 10 as shown in Figs. 5 and 7, and also a core H' which may be 105 a wood heel like that shown in Fig. 8 or Fig. 4, or a heel shaped core of any other suitable material may be used that corresponds with the heels that are to be operated upon. Babbitt metal is then poured 110 into the mold until level with the top of the latter. Upon cooling, the casting is removed from the mold and cut into two parts, one fast on the end of slide bar 13 and the other upon the end of shank 10. These two parts are then snagged and trimmed to reduce the 115 jaw 6 to the shape shown in Fig. 9 and the jaw 7 to a counterpart shape. The two jaws in their partially formed state are then assembled or incorporated in the machine. A wood heel is then placed in position upon the work holder and the machine operated. As the heel and cutter head are brought together the blades of the latter operate upon the breast sides of the relatively soft babbitt jaws 6 and 7 facing the cutter head 120 and give to the same a shape exactly conforming to, and coincident with the breast and shank portion of the heel. This final 125 shaping of the breast side of the rear jaw 130

6, after it is incorporated in the machine, by the cutters of the latter as they are set up for operating upon heels, is the distinguishing and important feature of the 5 method by which my new apparatus or machine is produced. As will be clear, the machine is in condition to operate upon wood heels after this first jaw shaping operation.

10 Other material than babbitt may be employed in making the jaws, particularly the jaw 6, and other methods than casting may be employed to properly shape its work engaging face and other parts preliminary to 15 the final shaping of the breast side thereof by the cutter head.

While I have herein shown my invention in connection with a machine of the kind illustrated and described in my patent above 20 referred to, it should be clear that the same may be used in conjunction with any type of machine for shank shaping the breast of a turned and grooved heel.

What I claim is:

25 1. A work holder for a machine of the character described having an abutment engaging that side of the heel where the cutter leaves the work to support the material of the same immediately adjoining the path of 30 the cutter against the lateral thrust of the latter, said abutment being molded with a heel engaging face that is a counterpart of and conforms to the shape of the side of the heel and having a corner adjacent the breast 35 of the heel coinciding with the corner at the side of the breast of a heel as finished by the cutter.

2. A work holder for a machine of the character described having an abutment engaging that side of the heel where the cutter leaves the work to support the material of the same immediately adjoining the path of the cutter against the lateral thrust of the latter, said abutment being molded with a heel engaging face that is a counterpart of and conforms to the shape of the side of the heel and having a corner adjacent the breast 45 of the heel coinciding with and supporting the material of the corner at the side of the 50 breast of the heel as finished by the cutter.

3. The method of producing apparatus for use in shaping wood heels which consists in constructing the holder of said apparatus with an abutment member molded with a 55 face that is counterpart of and fits against the side of the heel at which the cutter leaves the work to support the material thereof against the thrust of the cutter of the apparatus; then co-operatively combining said holder with cutting mechanism, and then 60 operating the apparatus to cause the cutting mechanism to trim and shape the breast side

of said abutment so as to provide said side with a corner adjacent said face coinciding with and supporting the material of the corner at the side of the breast of a heel as finished by said cutting mechanism. 65

4. The improvement in the art of making wood heels which consists in producing the work holder of the shaping apparatus by 70 first constructing the work holder with an abutment member for engaging the side of the heel at which the cutter leaves the work to support the material thereof against the thrust of the cutter of the apparatus; then 75 co-operatively combining said holder with cutting mechanism, and then operating the apparatus to cause the cutting mechanism to shape the breast side of said abutment so that said side conforms to and coincides 80 with the finished contour of the breasts of the heels shaped by the apparatus.

5. The improvement in the art of making wood heels which consists in producing the work holder of the shaping apparatus by 85 first constructing the same with an abutment member for engaging the side of the heel at which the cutter leaves the work to support the material thereof against the thrust of the cutter of the apparatus, said abutment 90 being a cast body of soft metal having the side thereof that engages the heel molded to a shape that is a counterpart of the shape of the portion of the heel engaged by it; then co-operatively combining said holder with 95 cutting mechanism, and then operating the apparatus to cause the cutting mechanism to shape the breast side of said abutment so that said side conforms to and coincides with the finished contour of the breasts of the 100 heels shaped by the apparatus.

6. A work holder for a machine of the character described comprising a pair of jaws engaging opposite sides of the heel to hold the latter in position while the heel is 105 being operated upon, the heel engaging face of each jaw being a counterpart of the portion of the heel engaged by it.

7. A work holder for a machine of the character described comprising a pair of 110 jaws engaging opposite sides of the heel to hold the latter in position while being operated upon, the heel engaging face of each jaw being a counterpart of the portion of the heel engaged by it, and each of said faces having a side edge adjacent the breast which conforms to and coincides with the adjacent corner at the junction of its side of the heel and the breast of the finished heel. 115 120

In testimony whereof I have affixed my signature.

NICHOLAS L. GULLIFORD.
